TORQUE RELEASE WRENCH

William M. Siesel, Verona, N. J.

Application November 19, 1937, Serial No. 175,361

12 Claims.

(Cl. 64—29)

This invention relates to torque overload release devices, being particularly concerned with improvements in torque limiting wrenches of a type adapted for field and shop use in connection with tightening nuts, bolts and the like on machinery.

In highly developed machinery such as aircraft and automotive engines, the correct tightness of nuts and bolts is a prime requisite for strength and safety, and the judgment of individual mechanics becomes too indeterminate in meeting requirements of tightness, since wrench length, strength of the individual and individual judgment are not controllable. Accordingly, a prime object of the invention is to provide a compact torque limiting wrench for universal utility, further objects being; the provision of a wrench which is extremely simple in design, and consequently, one that is easy and cheap to manufacture; the provision of a wrench that is light in weight, yet powerful, so that it is adapted for ownership by an individual mechanic and stowage in his portable tool kit; the provision of a wrench that is readily adjustable, over a wide range of torque limits which are predeterminate without calibration, so that the user may quickly preset the wrench according to the bolt or nut size on which he intends to operate; and the provision of a basic wrench unit which can be fabricated to take care of different orders of torque magnitude without major changes in the design of the parts.

Further objects will become apparent in reading the annexed detailed description in connection with the drawing, in which:

Fig. 1 is an end elevation, partly in section, and
35 Fig. 2 is a side elevation, partly in section.

The device comprises a driving member 10 consisting of a circular web 11 having an annular ring 12 integral therewith, the ring having a plurality of radial holes 13, equally circumferentially spaced, and of equal diameter. A driving collar 14 extends from the web 11, having opposed radial holes 15 for the insertion of a turning bar. The collar 14 may, if desired, be arranged as a standard wrench socket. Embraced by the ring 12 is a disc 16 having a plurality of radial holes 17 extending from the disc outer edge inwardly to an axial bore 18, the disc being rigidly mounted on a concentric hub 19 integral with a counterbored shaft 20. The bore 18 defines with the shaft 20 an open annulus, the left end thereof as shown, having a tapered conformation as at 21, so as to receive an axially movable collar 22 having a tapered or conical end as at 23. The collar 22 is preferably screw-threaded on the shaft 20 as at 24,

so that it may be accurately adjusted axially. Suitable lines and characters, as shown, may be scribed on the collar and disc members to serve as indicia for presetting the releasing torque for a range of nut or bolt sizes.

Within each hole 17 is a compression spring 26 engaging balls 27 and 28 and urging the balls apart into respective engagement with the ring 12 and the collar 22. The balls 27, when corresponding holes 13 and 17 are aligned, seat on the edges of the holes 13, which are of smaller diameter than the balls, preventing relative turning of the members 10 and 16 until the torque is sufficient to overcome the force of the springs 26, when the balls 13 move inwardly and permit relative rotation. Axial adjustment of the collar 22 presets the initial compression of the several springs 26, simultaneously, for torque release adjustment.

The order of torque to which the device is adapted may be controlled by the rate of the 20 springs used, and also by the diameter of the holes 13. It is contemplated that the balls 27 and 28 and the ring 12, in particular, be of wear-resistant material, such as case-hardened or nitrided steel.

The shaft 20 is provided at its right hand end 25 with a squared driving element 29 having a ball detent 30 adapted for use with standard wrench sockets or attachments. The web 11 is held in assembled relation on the shaft 20 by a bolt 31, threaded into the solid shaft end and being locked 30 thereto by a pin 32.

The device as above described is a distinct improvement over analogous devices of the prior art in several respects. One dominant feature is that the locking balls 27 act at nearly the extreme 35 outer diameter of the whole device, permitting of maximum torsional effect, due to the long moment arm afforded by the maximum radius of the device, while holding the bulk of the device to minimum size. As a specific example of the compactness of which a device according to the invention is capable, one capable of maximum torque release of 450 inch pounds weighs only two and a half pounds and is 3.8 inches in diameter and 2.4 inches long.

It will be noted that the major components of the device may be fabricated by simple turning and drilling operations from bar and flat stock with a minimum of wastage.

While I have described my invention in detail 50 in its present preferred embodiment, it will be obvious to those skilled in the art, after understanding my invention, that various changes and modifications may be made therein without departing from the spirit or scope thereof. I aim in 55

the appended claims to cover all such modifications and changes.

I claim as my invention:

5. A torque overload release device comprising a ring member having a plurality of circumferentially spaced radial holes, a disc member rotatably fitted within said ring having a similar plurality of radial holes, said disc having an axial bore, an arbor upon which said ring and disc are mounted, a conically formed collar slidable axially into said bore, a compression spring in each disc hole, a ball at each end of each said spring, the inner balls bearing on said collar and the outer balls bearing upon the inner surface 10 of said ring and upon the edges of the holes of the ring, said collar, according to its axial position, adjustably positioning the inner balls for initially compressing said springs, and driving attachments rigid with respective members.
15. 2. A torque overload release device comprising a ring member having a plurality of circumferentially spaced radial holes, a disc member rotatably fitted within said ring having a similar plurality of radial holes, said disc having an axial bore, an arbor upon which said ring and disc are mounted, a conically formed collar slidable axially into said bore, a compression spring in each disc hole, a ball at each end of said spring, the inner balls bearing on said collar and the outer balls bearing upon the inner surface 20 of said ring and upon the edges of the holes of the ring, said collar, according to its axial position, adjustably positioning the inner balls for initially compressing said springs, and driving attachments rigid with respective members, and means for adjustably positioning said collar in an axial sense.
25. 3. A torque overload release device comprising a circular web having a ring at its outer periphery, said ring having a plurality of radial holes around its periphery; a disc having a central hub, an annular bore, and radial holes opening to said bore; a conical-ended collar screwed on said hub into said bore, the conical end underlying said radial holes; balls in said holes contacting the collar; springs in said holes resting on the balls; and outer balls in said holes engaged between said springs and the inner surface 30 of said ring, said outer balls being registerable with the ring holes to hold said ring and disc from relative rotation.
35. 4. A torque overload release device comprising a circular web having a ring at its outer periphery, said ring having a plurality of radial holes around its periphery; a disc having a central hub, an annular bore, and radial holes opening to said bore; a conical-ended collar screwed on said hub into said bore, the conical end underlying said radial holes; balls in said holes contacting the collar; springs in said holes resting on the balls; outer balls in said holes engaged between said springs and the inner surface 40 of said ring, said outer balls being registerable with the ring holes to hold said ring and disc from relative rotation, and driving attachments respectively rigid with said web and hub.
45. 5. A torque overload release device comprising concentric members, one embracing the other, having an equal plurality of radial holes all in one plane normal to the axis of said members, the holes in the outer member being smaller than the holes in the inner member, spring-pressed 50 detents slidably engaged in each hole of the inner member, said detents being engageable with the hole edges in the outer member, and
55. unitary means for controlling the force on said spring-pressed detents.
6. A torque overload release device comprising concentric members, one embracing the other, having an equal plurality of radial holes all in one plane normal to the axis of said members, the holes in the outer member being smaller than the holes in the inner member, said detents being engageable with the hole edges in the outer member, a tapered collar axially movable relative to the inner member, and elements bearing on the collar taper and engaged in respective radial holes of the inner member for exerting an outward force on said spring-pressed detents. 10
7. A torque overload release device comprising a substantially cylindrical member having a plurality of angularly spaced radial guideways therein, an embracing ring member having apertures, spring-pressed detents in said guideways urged outwardly for engagement with said apertures when the latter are aligned with the guideways, and unitary means for coincidentally controlling the force on said spring pressed detents. 15
8. A torque overload release device comprising a member having a plurality of open-end guideways equally spaced about an axis of the member, a spring in each guideway, a detent pressed by each spring in one end of each guideway, a second member rotationally movable relative to the first member having recesses within which 20 said detents are adapted to engage, and unitary means movable on said first member for coincidentally adjusting the several springs for pre-setting the amount of torque necessary between said members to unseat the detents from said 25 recesses.
9. A torque overload release device comprising a circular member having a plurality of guideways formed therein, a second member having a plurality of recesses, detents in the guideways 30 engageable with the recesses, springs in said guideways pressing respective detents, and unitary means for coincidentally adjusting the force exerted by said springs on said detents. 35
10. A torque overload release device comprising a circular member having a plurality of guideways formed therein, a second member having a plurality of recesses, detents in the guideways engageable with the recesses, springs in said guideways pressing respective detents, and unitary means adjustable axially of said circular member for coincidentally adjusting the force exerted by said springs on said detents. 45
11. A torque overload release device comprising a substantially cylindrical member having a plurality of angularly spaced substantially radial guideways therein, said member having a central bore, an embracing ring having apertures registerable with said guideways, spring pressed detents in said guideways, and a bushing 50 in said bore the surface of which provides a bottom rest and reaction member for the springs of said detents, said detents being urged outwardly into engagement with said ring. 60
12. A torque overload release device comprising a member having a plurality of radial guideways therein, detent elements, movable in said guideways, an apertured ring embracing the member the apertures thereof being registerable with said detents, springs urging said detents into engagement with said apertured ring, and a movable concentric element in said member engaged by said springs and forming a reaction member therefor. 65
